SPRING FOUNDATION FOR UPHOLSTERED
FURNITURE

Albert M. Bank, Jersey City, N. J.

Application August 19, 1944, Serial No. 550,220

9 Claims. (Cl. 155—179)

1

This invention relates to spring foundations for upholstered furniture. It is particularly directed to an anchor or bracket for connecting an end of a zig-zag spring to the seat frame. This application is a continuation in part of application Serial No. 530,609, filed by applicant April 12, 1944, and now Patent No. 2,439,789, granted April 20, 1948.

An object of this invention is to provide a highly improved anchor attachable to the upper end of a wall of a seat frame and onto which one end of a zig-zag spring may be quickly and easily engaged, and which will prevent the spring from accidentally becoming disengaged.

Another object of this invention is to provide a bracket of the character described which may be made of stamped sheet metal, and which may be attached to a wall of a seat frame by a pair of nails or the like fastening means, and having a hooked portion to engage one leg of a bent back end abutment loop of a zig-zag spring, and a portion to engage beneath the other leg of the abutment loop, the construction being such that the abutment loop may be easily engaged with the bracket after the bracket has been attached to the frame, by a hooking action.

Yet another object of this invention is to provide a bracket of the character described having a portion formed with openings to receive fastening means for attaching the bracket to the seat frame, an integral hook portion to engage with one leg of a bent back abutment end loop of a zig-zag spring, and a portion interposed between the other leg of the abutment loop and the top wall of the frame, whereby to prevent said outer leg from contacting the frame.

Still another object of this invention is to provide a compact and durable spring anchor of the character described which shall be relatively inexpensive to manufacture, easy to attach to a seat frame, and which will firmly and securely anchor one end of a zig-zag spring to a seat frame, and which shall be practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention,

2

Fig. 1 is an elevational view of a spring seat embodying the invention;

Fig. 2 is a partial top plan view thereof;

Fig. 3 is a partial perspective view showing one end of a spring clamp to a seat frame wall by a clamp embodying the invention;

Figs. 4, 5, 6 and 7 are views similar to Fig. 3 and illustrating modified forms of the invention.

Fig. 8 is a side elevational cross sectional view of a spring foundation embodying the invention, and provided with a spring edge construction;

Fig. 9 is a partial, top plan view thereof.

Fig. 10 is a perspective view of a spring employed in the spring edge construction in Figs. 8 and 9.

Fig. 11 is for a similar construction of Fig. 9 and illustrating a modified construction.

Referring now in detail to the drawing, **10** designates a spring foundation for upholstered furniture. The same comprises a frame **11** and a plurality of zig-zag springs **12** mounted thereon and attached thereto by means of front brackets or anchors **13** and rear brackets or anchors **14**.

The frame **11** may be made of wood and comprises side walls **15**, a front wall **16**, and a rear wall **17**. The zig-zag springs **12** may be longitudinally arched as shown in the drawing. At the ends of each spring are bent back loops **20**. Each loop **20** comprises an end leg **21**, and a next to the end leg **22** connected thereto by a curved or semi-circular portion **23**.

The bent back abutment loops **20** of spring **12** are attached to the front and rear walls **16** and **17** respectively by the brackets **13**, **14**. Said brackets may be similar in construction if desired, or the rear bracket may be constructed as shown in my Patent No. 2,257,633, issued September 30, 1941.

Spring **12** is connected to bracket **13**, in the manner shown in Fig. 3. Front bracket **13** may be made of stamped sheet metal and comprises a vertical wall **26** contacting the outer surface of frame wall **16**. Wall **26** may be formed with a pair of through openings to receive nails **28** or other fastening means driven into the frame wall for attaching the clamp to the frame wall. Wall **26** extends to the upper end of the frame wall. Extending from wall **26** is a horizontal hooked or channelled wall **29** contacting the upper surface of the frame wall **16**. The channel wall **29** forms a channel or groove **29a** which opens outwardly of the frame. Extending from the channel wall **29** is a bent back wall **30** which may be inclined downwardly to contact the upper surface **16a** of

frame wall 16. If desired, wall 30 may be curved downwardly and formed at its end with an upwardly curved lip 39a to confine arm 21 of the end loop.

It will be noted that the leg 22 of the abutment loop 20 is engaged within the channel 29a formed by the channel wall 29. Leg 21 of the abutment loop contacts the upper surface of bracket wall or portion 30. It will be noted that the width of the bracket is less than the width of spring 12 so that the bracket can fit within the abutment loop 20. One end of the spring may be first connected to rear bracket 14. The other end may then be grasped by any suitable tool and hookingly engaged with bracket 13. The connection of the front end of the spring with bracket 13 is therefore quick and easy. After it is connected it will not accidentally come out of the bracket. When pressure is applied to the spring as by a person sitting on the seat, leg 21 will be forced downwardly on wall 30 which protects the wood frame wall from the spring. The hook or channel 29 firmly engages a leg 22 of the abutment loop to anchor the spring to the frame.

In Fig. 4 there is shown a bracket illustrating a modification, embodying the invention for anchoring one end of the spring 12 to a seat frame wall. Bracket 40 may be made of sheet metal and comprises a flat narrow wall 41 contacting the top surface 16a of frame wall 16. Said wall 41 is formed adjacent the ends thereof with openings to receive nails or fastening means 42 driven downwardly into the frame wall. Extending from wall 41 is a channel wall 43 forming a hook or channel opening outwardly. Bent back from channel wall 43 is a wall 44 inclined rearwardly and downwardly and contacting the top surface 16a of frame wall 16. Wall 44 is formed with an upwardly curved lip 44a at its end to confine leg 21. It will be noted that channel wall 43 as well as the part of wall 44 adjacent thereto are formed with notches or cutouts 45 at the opposite ends thereof, whereby said channel wall and adjacent wall are narrower than wall 41 or the outer end of wall 44. This construction exposed the nail holes and permits nails to be driven downwardly through said openings. Spring 12 is engaged with bracket 40 in the same manner as it is engaged with clamp 13. Leg 22 is received within a channel formed by wall 43 and leg 21 contacts the top of wall 44.

In Fig. 5 there is shown a bracket 50 illustrating another form of the invention. Bracket 50 is also made of sheet metal and comprises a front wall 51 formed with openings for nails 28, and contacting the front surface of the frame wall 16. Extending from wall 51 is a bent back curved channel wall 52 from which there extends an inwardly and downwardly inclined wall 53. Bracket 50 is similar to bracket 13 except that wall 53 is formed with a pair of parallel slits 55, and the metal between the slits is pressed upwardly to form a strap 56. Leg 21 of the abutment loop 20 extends between the strap 56 and wall 53. Leg 22 of the abutment loop engages the channel wall or hook 52.

In Fig. 6 there is shown a bracket 60 similar to bracket 50 except that the wall 53 thereof is formed with slits 55 and the metal between said slits is pressed downwardly to form a strap 61. Leg 21 of the abutment loop then passes beneath wall 53 and between said wall and the strap 61 as clearly illustrated in the drawing.

In Fig. 7 there is shown a bracket 70 for 75

anchoring one end of the spring 12 to a frame wall 16. Bracket 70 comprises a front wall 71 contacting the outer surface of the frame wall and formed with openings to receive nails or other fastening means 28 for attaching the bracket to the frame wall. Extending from the upper end of wall 71 and resting on the upper surface of the frame wall is a horizontal hook or channel wall 72. Extending from the channel wall 72 in an inward and horizontal direction is a wall 74. Extending from the rear end of wall 74 is an upwardly inclined wall 75. Wall 74 is formed adjacent each of the side edges thereof with a pair of horizontal slits 76 forming tabs 77 bent downwardly and contacting the upper surface of the frame wall.

It will be noted that the tabs 77 are adjacent the upwardly bent wall 75. Leg 21 of the end abutment loop of the spring 12 contacts the top of wall 74 and abuts against wall 75. Leg 22 of the abutment loop engages within the channel or hook 73 formed by wall or hook 73 as with the other brackets.

Referring now to Figs. 8, 9, and 10, there is shown a spring foundation or spring seat construction 10a, comprising a seat frame 11 having side walls 15, a front wall 16, and a rear wall 17. Mounted on front and rear walls are zig-zag springs 12 attached to the frame by means of brackets such as shown in Figs. 3 to 7 of the drawing.

It will be noted that the springs 12, as shown in Fig. 9, are similar in construction, so that the loops 80 pointing in one direction are in alignment, whereas the loops 81 pointing in an opposite direction, are also in alignment.

Mounted on each pair of adjacent springs 12 is a cantilever spring 83. Spring 83 comprises a pair of legs 84 and 85, interconnected by an interconnecting portion 86.

Spring 83 is made of a single piece of wire. The leg 84 is shorter than leg 85. At the outer end of leg 84 is an outwardly bent hook 87. At the outer end of leg 85 is an outwardly bent hook 88. The manner of mounting spring 83 on a pair of adjacent springs 12 is illustrated in Figs. 8 and 9 in the drawings.

As shown in the drawings, leg 84 passes beneath a pair of adjacent runs 89 of one spring 12, and the hook 87 engages a next adjacent loop 81 disposed on the outer side of spring 12. Leg 84 therefore rests on a run 90 of spring 12 adjacent to the runs 89 beneath which said leg passes.

Leg 85 passes beneath a pair of adjacent runs 91 of the next adjacent spring 12 and the hook 88 engages a loop 92 of said spring 12. The leg 85 is longer than leg 84 and hook 88 engages a loop further along the spring than the loop which is engaged by hook 87. Leg 85 rests upon run 93 of spring 12 next adjacent to the runs 91.

Interconnecting portion 86 is located between the springs 12, as shown in Fig. 9 of the drawing. The legs 84 and 85 may be normally substantially parallel and opened up when engaged with the springs 12.

The springs 83 may be interconnected by an edge wire 95 having end legs 96 formed with hooks 97, engaging the end springs 12. Edge wire 95 is attached to springs 83 by clips 93a. It will thus be noted that each spring 83 acts as a cantilever spring and is supported on a pair of adjacent springs 12, thereby providing a highly proficient spring edge construction.

In Fig. 11 there is shown a spring seat con-

struction 106, likewise comprising a frame 11 on which are mounted a plurality of zig-zag springs 12, supported on the ends thereof by brackets such as shown in Figs. 3 to 7 of the drawing.

It will be noted that each pair of adjacent springs 12 are symmetrically disposed to one another, so that the inwardly extending loops of the adjacent springs are in alignment with each other, and outwardly pointing loops of adjacent springs are likewise in alignment with each other.

Supported on each pair of adjacent springs 12 is a cantilever spring 109. Spring 109 comprises a pair of similar symmetrically disposed legs 101, interconnected at adjacent ends by a portion 102. At the ends of legs 101 are outwardly extending hooks 103.

The legs 101 are of similar length and the hooks 103 engage aligned outwardly pointing loops of the spring. Each leg 101 likewise passes beneath a pair of adjacent runs 106 of the zig-zag springs, and is supported by an adjacent run 107.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. In a spring foundation for upholstered furniture, a frame having an end bar, a spring having a longitudinally extensible body and a loop at its end formed with inner and outer legs connected by a portion extending between their ends and having its inner leg spaced from the body of the spring, and an anchoring bracket for said spring formed from a strip of stiff metal bent intermediate its length to form a channeled seat extending transversely of the bracket and open along its outer side and upper and lower tongues extending from upper and lower walls of the seat, the lower tongue extending downwardly from the seat against the outer side face of said bar and secured by fasteners passing through openings in the lower tongue and into said bar and the channeled seat resting flat upon the upper face of the bar, said upper tongue extending from the outer side edge of the upper wall of the seat in spaced relation to the seat and beyond the seat at a downward incline with its free end bearing against the upper face of the bar and terminating in an upwardly projecting lip, and said spring having its loop fitting about said bracket with its outer leg fitting into said seat and its inner leg extending across the upper face of the upper tongue and said lip projecting upwardly between the inner leg and the body of the spring.

2. In a spring foundation for upholstered furniture, a frame having an end bar, a spring having a body and a loop at an end thereof extending transversely of the body and having inner and outer legs, and an anchoring bracket for said spring formed of stiff metal and comprising a channeled seat resting flat upon the upper face of said bar and being open along its outer side and having upper and lower walls connected by an inner side wall, and a tongue extending from the outer side edge of the upper wall at a down-

ward incline across said seat with its free end resting upon the upper surface of said bar and formed with an upwardly projecting lip, said loop being disposed about said bracket with its outer leg engaged in said seat and its inner leg extending across and resting upon the upper tongue adjacent said lip with the lip projecting upwardly between the loop and the body of the spring.

3. An anchoring bracket for a spring having a body and a loop at its end, said bracket comprising a strip of stiff metal bent intermediate its length and forming a transversely extending channeled seat open along its outer side and upper and lower tongues extending from upper and lower walls of the seat along the open outer side thereof, said lower tongue extending downwardly from the lower wall of said seat and being formed with fastener-receiving openings and said upper tongue extending from the open side of the seat across the upper wall in spaced relation thereto and beyond the inner side of the seat at a downward incline and terminating in an upwardly projecting lip, the junction of the lip with the upper tongue being disposed in the plane of the lower wall of the seat.

4. An anchoring bracket for a spring having a body and a loop at its end, said bracket comprising a channeled seat having upper and lower walls and an inner side wall and being open at its ends and along its outer side, means being provided for securing the bracket to a support with the lower wall of the seat resting flat upon the support, and a tongue extending from the outer side edge of the upper wall and across the upper wall and beyond the inner side of the seat at a downward incline and terminating in an upwardly projecting lip disposed in the plane of the lower wall of the seat.

5. In a spring foundation for upholstered furniture, a frame having an end bar, a spring having a longitudinal body and a loop at its end formed with inner and outer legs connected by a portion extending between their ends, and an anchoring bracket for said spring formed from a strip of stiff metal bent intermediate its length to form a channeled seat extending transversely of the bracket and open along its outer side and upper and lower tongues extending from upper and lower walls of the seat, the lower tongue extending downwardly from the seat against the outer side face of said bar and secured to said bar and the channeled seat resting flat upon the upper face of the bar, said upper tongue extending from the outer side edge of the upper wall of the seat in spaced relation to the seat and beyond the seat at a downward incline with its free end bearing against the upper face of the bar, and said spring having its loop fitting about said bracket with its outer leg fitting into said seat.

6. In a spring foundation for upholstered furniture, a frame having an end bar, a spring having a longitudinal body and a loop at its end formed with inner and outer legs connected by a portion extending between their ends, and an anchoring bracket for said spring formed from a strip of soft metal bent to form a channeled seat extending transversely of the bracket and open along its outer side, the channeled seat resting flat upon the upper face of the bar, an upper tongue bent back and extending from the upper wall of the seat, and beyond the seat, with its free end bearing against the upper face of the bar, and said spring having its loop fitted

about said bracket with its outer leg fitted into said channeled seat and its inner leg pressing down against said upper tongue, and means for fastening said bracket to said bar.

7. In a spring foundation for upholstered furniture, a frame having an end bar, a spring having a longitudinal body and a loop at its end formed with inner and outer legs connected by a portion extending between their ends, and an anchoring bracket for said spring formed from a strip of soft metal bent to form a channeled seat extending transversely of the bracket and open along its outer side, the channeled seat resting flat upon the upper face of the bar, an upper tongue bent back and extending from the upper wall of the seat, and beyond the seat, with its free end bearing against the upper face of the bar, and said spring having its loop fitted about said bracket with its outer leg fitted into said channeled seat and its inner leg pressing down against said upper tongue, and means for fastening said bracket to said bar, and a second tongue extending downwardly from the lower wall of said seat and contacting the outer surface of said bar.

8. A bracket for anchoring one end of a spring to a bar of a spring frame, comprising a member made of a strip of soft sheet metal, said member having intermediate its length a channeled seat extending transversely of the bracket and open along its outer side, and adapted to rest on the top surface of the bar, a lower tongue extending downwardly from the lower wall of said seat, and adapted to contact the outer surface of the bar, a bent back portion extending from the upper wall of the seat and disposed over said upper wall, a top tongue extending from said bent back portion toward the top surface of the bar and toward the inner surface of the bar.

9. A bracket for anchoring one end of a spring

5 to a bar of a spring frame, comprising a member made of a strip of soft sheet metal, said member having intermediate its length a channeled seat extending transversely of the bracket and open along its outer side, and adapted to rest on the top surface of the bar, a lower tongue extending downwardly from the lower wall of said seat, and adapted to contact the outer surface of the bar, a bent back portion extending from the upper 10 wall of the seat and disposed over said upper wall, a top tongue extending from said bent back portion toward the top surface of the bar and toward the inner surface of the bar, and an upwardly turned lip at the front end of said top tongue.

15 ALBERT M. BANK.
